UNITED STATES PATENT OFFICE

2,544,878

HEEL CONSTRUCTION

Samuel L. Dratler, Cleveland, Ohio

Application September 20, 1948, Serial No. 50,210

1 Claim. (Cl. 36—36)

2

My present invention pertains to the art of ladies' shoes of the high heeled type, and involves primarily novel construction of heel of composite formation.

The primary object of my invention has been to design a heel of the class mentioned which comprises especially a hollow plastic or equivalent hard substance body so that the exposed side portion of the heel will be highly resistant to scuffing and marring, said body being used in conjunction with a filler body of wood, or not, as may be preferred, and there being provided novel means for attaching the lift commonly used in these heels to the body.

My invention involves other details of construction of the heel assembly, an understanding of which will be had upon reference to the following detailed description, in conjunction with the accompanying drawings.

In the annexed drawings:

Figure 1 is a fragmentary side view of a ladies' shoe, the heel portion of which embodies my present invention, and is illustrated in sectional manner to bring out the details of this construction.

Figure 2 is a view of the hollow body of the heel alone, looking down thereon as when detached from the shoe.

Figure 3 is a bottom view of the wooden or equivalent filler body which may be used in connection with the hollow body of the heel, alone.

Figure 4 is a view similar to Figure 1 but showing a modification of the invention in which the wood or equivalent filler body is dispensed with.

Referring to the drawings accompanying my application, the construction of the form of my invention shown in Figures 1 to 3 is specifically described as follows:

As seen in Figure 1, the body of the shoe is designated generally as A and this shoe is of the ordinary type used by ladies with respect to the general mode of making the same, with the exception of the heel construction. The heel construction is of the high heel type, generally so-called, and the novel heel of my present invention includes primarily the hollow body 1, preferably made of plastic, and having the general conformation and sectional external area of the ordinary high heel employed in shoes of the class described and which usually comprises a wooden body covered by a leather covering, or sometimes employed without such covering.

The hollow body 1 of my heel tapers generally toward the lower end thereof and is preferably made of plastic material of hard nature suitably

molded so that the body 1 is open at its top portion where the edges thereof engage the bottom of the shoe A at the heel end of the shoe. The hollow portion of the body 1 extends downwardly substantially the entire length of the body and is closed at the lower end by the bottom section 2 which is formed, however, with a downwardly extending edge flange 3 projecting from the plane of the bottom portion 2 a short distance relatively to the whole vertical dimension of the body 1. The formation of the flange 3 provides a shallow recess at the lower end of the body 1, surrounded by the said flange 3.

In the construction of my invention shown in Figures 1, 2 and 3, I contemplate providing a solid filler body 4 which may be made of wood or equivalent material and which is received in the hollow portion of the member 1 and is formed in contour to fit snugly within this said portion 20 of the part 1.

Projecting centrally upward from the bottom member 2 of the body 1 a distance of about two-thirds the extent from said bottom member 2 to the top of the member 1 is a tubular extension 5, the bore 6 of which is screw threaded, and said bore extends entirely through the extension 5 and through the bottom member 2 referred to. The extension 5 is preferably integrally molded or formed with the plastic body 1 in the manufacture thereof. For attaching the filler body 4 within the hollow body 1 of the heel I provide a screw 7 which passes downwardly from the top of the filler body 4 through a suitable opening in the latter and engages the screw threaded bore 35 6 of the extension 5 near the upper portion of said bore.

The recess at the bottom of the member 1 provided by the flange 3 extending in line with the periphery of the heel as previously referred to, is designed to receive the upper reduced portion of a lift 8 which may be made of rubber, leather, or any suitable cushion material. The lift 8 is attached to the bottom member 2 and flange portion 3 of the body 1 by means of a screw 9 which passes through a central opening in the lift and has its screw threads interengaged with the threaded central bore or opening 6 of the extension 5 previously referred to.

It will be apparent that a heel of the construction above described may be assembled quite readily by emplacing the filler body 4 in the hollow body 1, connecting the parts 4 and 1 by the screw 7, and by emplacing the lift 8 in the recess surrounded by the flange 3 and connecting 55 said lift to the bottom and flange portion of the

member 1 by means of the screw 9. Under these conditions a heel unit is provided which is adapted to be attached to the base of the shoe at the heel portion thereof by means of the nails 10 as seen in Figure 1, according to regular practice.

The renewal of the lift 8 is a very simple operation, merely involving the removal of the screw 9, replacement of the lift with a fresh one, and the replacement of the screw 9.

By reason of the formation of the hollow body 1, the objectionable scuffing or marring of the heel is resisted to a maximum extent, as compared with the scuffing of ordinary leather covered heels.

In Figure 4 I have illustrated a modification of my invention in which the filler body 4 previously described with regard to the construction of Figures 1 to 3 inclusive, is dispensed with. In Figure 4 the heel is comprised of the main hollow body 11, the bottom portion of which is of greater thickness than that of the member 1 shown in Figure 1, but is equipped with the bottom flange 12 in a somewhat similar manner to the construction first described. The lift 13 is mounted on the lower or bottom portion of the body 11 and screws or like fastenings 14 are employed to attach the heel portion of the shoe body to the upper ends of the heel body 11. In this construction the lift 13 is held from displacement from the lower portion of the heel body 11 in much the same way as in the construction of Figure 1 except in Figure 4 there is employed a screw 15 passing through the center of the lift 13 and entering a threaded recess in the body 11.

The lift 8 and lift 13 of my heel constructions have their peripheral portions extended to underlie the flanges 3 and 12, respectively, as seen in Figures 1 and 4, respectively.

The threads of screws 14 enter and interengage the threads of threaded openings 16 in the heel

body 11 for attaching the latter to the shoe body.

Having thus described my invention, what I claim as new and desire to secure by Letters Patent of the United States, is:

5 In a shoe heel, in combination, a hollow body open at its upper end and having a closing bottom portion at its lower end, said bottom portion having a tubular integral extension projecting up therefrom within the hollow body portion, the said tubular extension having an interiorly threaded bore, a filler body disposed in said hollow body and having a recess to receive said extensions and having its upper surface flush with the top walls of said hollow body, said bottom portion having a downwardly extending edge flange forming a recess on its under side, a lift seated on said bottom and in said recess, a fastener attaching the lift to the center portion of the bottom portion and having threads to engage the threaded bore of said tubular extension, and a fastener attaching the filler body to the hollow body and having threads to interengage the threaded bore of the tubular extension.
